UNITED STATES PATENT OFFICE.

WILLIAM A. ZEIDLER, OF NEW YORK, N. Y.

IRONING MACHINE.

Application filed July 2, 1920. Serial No. 393,498.

To all whom it may concern:

Be it known that I, WILLIAM A. ZEIDLER, a citizen of the United States, residing at New York, in the State of New York, have 5 invented a new and useful Improvement in Ironing Machines, of which the following is a specification.

This invention relates to ironing machines, and has for its objects the provision 10 of a machine designed especially for domestic use which shall be lighter and less expensive than other machines while being rapid and efficient in action; the provision of a machine wherein the area of contact between the work and the heated member shall 15 be large and the area of contact between the work and the pressing rollers shall be small to the end that steam may be evolved freely and the ironing performed rapidly; the provision of a plural roll machine having new and improved means of driving, supporting, and adjusting the rolls; the provision of a new and improved type of domestic ironer; while further objects and advantages will 20 become apparent as the description proceeds.

In the drawings accompanying and forming a part of this application I have shown certain physical structures in which my invention can be embodied although it will 30 be understood that these drawings are intended to be merely illustrative and not limiting.

Figure 1 is a side elevation of my improved machine;

Figure 2 is a top plan view, partly broken away;

Figure 3 is a cross section through the rollers and table, other parts being broken 40 away;

Figure 4 is a perspective of the foot pedal and members interconnected therewith;

Figure 5 is a detail of part of the roller driving mechanism;

Figure 6 is a fragmentary side elevation, partly in section, of the standards mounting a modified form of my invention;

Figure 7 is a fragmentary plan view of Figure 6;

Figure 8 is a top view of the rod 52 and immediately adjacent pedal portions.

In the embodiment of my invention there is provided a frame including a pair of standards 2, mounting a table 3, upon which 55 table is superposed a secondary pair of

standards 4 carrying a U-shaped sheet metal plate 5, upon the front bight part of which carried by this table is a heated member 8 provided with any suitable heating means such as the gas burner 9 fed by a pipe 10. 60 One part of the plate 5 bears a feed table 6 provided with a thin lip 7 projecting close to the heated member.

Beneath the burner 9 a guard screen 11 is hung, which extends full around the lower 65 and side parts of the hot plate 8.

Pivoted at 12 upon upstanding arms 38 at the rear ends of the plate 5, there are forwardly articulated levers each including the fulcrum arm 13 and forearm 13', pivoted 70 at 15 on the former. Upon the extremities of the arms 13' there is mounted a roller 14 and between the arms 13 intermediately of their length a roller 14' is mounted. The rollers have an endless chain connection by 75 which they are caused to rotate with the same peripheral speed. The arm 13' is connected resiliently with a lever 16 of the first class by a link 17, connected to a sliding collar 18 on the link seated against a spring 80 19 secured at the lower end of the link. The lever 16 is fixed on a transverse fulcrum shaft 20 mounted beneath the table 3, upon which shaft a lever 21 is also fixed in alignment with the lever 16 and forming therewith a bellcrank, the lever 21 being connected by a link 22 to a pedal lever 23, yielding supported by a spring 24 and pivoted 85 adjacent the bottom of the frame at 25 in a U-shaped bracket 26. The lever 16 is 90 provided with a latch member 27, engaging a rack segment 28, mounted on the table 3, the teeth of the ratchet being so formed that downward movement of the lever 16 is resisted, while the upward movement is 95 checked. Depression of the foot pedal 23 will thus cause an upward movement of the lever 16 upon the release of the said latch from the said ratchet. The plate 8 is formed with a transverse gutter 8', the rear 100 side of which is so curved and located as to fit snugly to the roller 14 when lowered, while the front side of the gutter slopes gradually upward to a level with the plate 7.

Mounted upon the table 3 there is a motor 29, connected by a belt 30 with a pulley 31, on a shaft 32, the shaft 32 being mounted upon one lever 13 with the pulley in such position that movement of the lever 13 will not affect the proper operation of the belt 110

30. Upon the shaft 32 there is a worm 33 meshed with a worm gear 34 on the shaft of the roller 14' which carries a sprocket 35 driving the chain 36 and thereby another 5 sprocket 37 on the roller 14. At the other end of said rollers, like sprockets 35' and 37' are provided.

The hot plate 8 terminates to the rear of the roller 14' and a clearway 40 is provided 10 through which fabrics may pass downwardly from the hot plate, and in the direction of the arrow 41, upon a sheet metal, or other suitable curved plate 42, the form of the plate being such that with the stiffness imparted by the ironing, fabrics will be projected forwardly thereon conveniently to 15 the hand of an operator. This permits a single operator to both feed the machine and receive the finished work therefrom.

20 In the ironing operation, the work is placed upon the table 6, and fed beneath the roller 14, by which the pieces are drawn rearwardly, passing under the roller 14 and thence downwardly, forwardly and upwardly as before described. The roller 14 may be elevated to any predetermined position, by means of the flexed lever 13 and its 25 cooperating part 13', the relative movement of the two parts of this lever being limited in the upward movement thereof by the stop 30 43; that is to say, the upward movement of the lever 13' will, upon reaching the limit fixed by said stop, cause the upward movement of said lever 13, but, upon the downward movement of the lever 13' by the rod 35 17, when the roller 14' engages the plate 8 or work thereon the roller 14 will continue in its downward movement until it reaches the limit of the bottom of the recess 8', less 40 the thickness of the work therein.

In the modified form shown in Figs. 6, 7, and 8, the shaft 20 has fixedly mounted thereon three members, including two end arms 44 and 45 and a central arm 46, the 45 member 46 being a lever centrally mounted and provided with a bifurcated end 46', the members 44 and 45 being levers provided with respectively bifurcated ends 44' and 45'. The shaft 20 is loosely mounted upon 50 an internal ratchet segment 47, which segment is held from rotation by a shaft 48, which shaft 48 extends the full length of the machine and is anchored to table 3. A pawl 49 pivotally mounted at 50 engages in 55 teeth 51 of said ratchet segment. The said pawl is a right-angled bent-over extension of a vertical shaft 52, which as pivoted at 50 upon its rotation engages and disengages the pawl from the teeth 51. In order to compensate for the angular movement of the lever 46, to which the shaft 52 is connected, a pivot 53 is provided, which pivot 53 is 60 between the bifurcations 46' of the lever 46.

Pivoted at 54 to the standards 2 is a pedal 65 55 provided with an eye 56 and yieldingly

supported by a spring 24', said eye receiving the lower end of the shaft 52 as indicated at 57.

Fixedly mounted on the shaft 52 there is a rudder 58, which rudder is yieldingly held 70 in alinement with the pedal lever 55 by a helical spring 59, but upon pressure of the toe in a clockwise direction as shown in Figure 8, the shaft 52 is rotated, turning the pawl 49 from engagement with the teeth 75 51, which permits the spring 24' to lift the pedal 55 and lower the fixed levers 44 and 45, thereby pulling downward upon the lever 17. When the pedal is depressed, the ratchet arm rides over the teeth 51 which 80 are inclined for the purpose, whereby the said lever 46 will become set at whatever position it may be when downward movement of the pedal ceases, thereby regulating the degree of pressure on the rolls 14 and 85 14' in stages suitable to various fabrics. For instance, the upper stop may give the greatest pressure; the second stop give a lighter pressure; the third stop is operative when the roll 14 is raised slightly from the 90 ironing bed for heavy work, and the lowest stop disengages the rolls entirely, which permits the irons to be cleaned easily, as preferably the predetermined lift of this lowest stop causes the front roll to be raised about 95 three inches, and the rear one about one inch.

It will be obvious that the modified form permits full control of the rod 17 by the foot alone, and in a simple and efficient 100 manner.

The space between the forward sloping part and the roller 14 may be termed a throat space, and the fabric passing from the forward part of the table will readily enter this throat without notable bending, obviating the need for a feed apron in advance of the roller 14, and without requiring the hands of the operator to be brought 105 near the throat.

The lip plate 7 being very thin conducts but little heat from the plate 8, and radiates so much, that the feed table 6 is not detrimentally affected. The space between the lip plate and hot plate is so extremely small 115 in practice that work passes thereacross as though on a continuous surface, and the surfaces of the feed table and hot plate may be termed a practically continuous feed surface.

What I claim to be new is:

1. In an ironing machine, a heated member supported in a substantially horizontal position, a frame pivoted to each end of said member, a pair of parallel horizontal rollers journaled in said frame and located above and in operative relation to said heated member, and means for raising and lowering said frame, said frame having an articulation between said rollers whereby 125 130

the latter may exhibit a limited vertical movement relatively to each other.

2. A domestic ironing machine, comprising a frame, a heated member supported by said frame in a substantially horizontal position, and two spaced, parallel, horizontal, padded rollers located above said heated member and in operative relation thereto, bearing members for said rollers located at opposite ends thereof and pivoted to said frame at the side away from the operator, means for driving said rollers in the same direction, and pedal means for swinging said bearing members about their pivots so as to raise said rollers simultaneously away from said heated member.

3. In a domestic ironing machine, a heated member supported in a substantially horizontal position, a pair of spaced, parallel, horizontal padded rollers located above said heated member and in operative relation thereto, means for revolving said rollers in the same direction, means for depressing said rollers with varying pressures while leaving said rollers free to move vertically independently of each other in accordance with the thickness of articles passing therethrough, a pedal adapted when depressed to elevate both said rollers away from said heated member, and means for locking said pedal in depressed position.

WILLIAM A. ZEIDLER.
